CLAIM

The ornamental design for a lighter, as shown and described.

DESCRIPTION

FIG. 1 is a perspective view of a lighter showing my new design including the top, front and one side thereof;

FIG. 2 is a top plan view thereof;

FIG. 3 is a rear elevational view thereof; and

FIG. 4 is an enlarged fragmentary sectional view taken along line 4—4 of FIG. 1.

The bottom of the lighter and the side of the lighter opposite that shown in FIG. 1 are substantially plain and unornamented.
